MACHINE FOR FORMING HEEL FLAPS

Louis Sabo, Astoria, N. Y., assignor to Herman B. Delman, New York, N. Y.

Application February 25, 1942, Serial No. 432,313

8 Claims. (Cl. 12—17)

This invention relates to the art of shoemaking. The object of my invention is to provide a machine for use in forming the breast flaps for heels.

A further object is to provide means for supporting a shoe in proper position in the machine relative to the forming means, to form the flap so that it will accurately fit the breast of the heel of either a right or a left side shoe; the operation being performed after the heel has been temporarily or permanently secured to the heel seat of the shoe.

A further object is to provide a machine that is light in weight, will operate practically without noise, and will operate in successive steps, each step being under control of the operator.

A further object is to provide a register for counting the steps of the machine, each step corresponding to the act of forming a flap in the machine.

Certain details of construction used in connection with the present machine, and not specifically described herein, are set forth in my co-pending applications, as follows: Serial No. 358,442, filed September 26, 1940; Serial No. 419,522, filed November 18, 1941; and Serial No. 420,837, filed November 28, 1941.

Referring to the drawings which form a part of the specification,

Fig. 1 is a front elevational view of a machine designed for the purpose above set forth, and also shows the means, comprising an electric motor, for driving the machine, and means for connecting and disconnecting the driving means relative to the main shaft of the machine;

Fig. 2 is a side view of the cam used in driving the forming means, such as a die;

Fig. 3 is a side elevational view showing a shoe resting in supported and adjusted position, ready for the forming operation;

Fig. 4 is a perspective view of the carriage and adjustable parts carried thereby for adjusting the position of the shoe relative to the die;

Fig. 5 is a perspective view of the carriage and the platen, with their supporting parts;

Fig. 6 is a perspective view of a fragmentary portion of the supporting means for the shoe, on an enlarged scale; and

Fig. 7 is a horizontal fragmentary sectional view taken approximately on the line 7—7 of Fig. 5.

10 indicates a base frame, 11 a shelf which serves to brace the frame, and 12 an electric motor resting on the shelf; 13 indicates a reduction speed gear enclosed in a housing, and serv-

ing to reduce the speed from a small high-speed motor, required to rotate the main shaft 14 at the top of the machine.

15 A lower shaft 14' is driven by the reduction gear, and carries a rotary clutch member 15 slideable on the outer end thereof, which is driven by a feather 16 fixed in the shaft. The member 15 is provided with an annular groove 17. A lever 18, pivoted at 19 and bifurcated at 20, rests in said groove and actuates the clutch member when the pedal 21 is depressed against the pressure of the spring 22 resting thereunder.

15 A stanchion 23 carries a short shaft 24, on which is mounted a loose pulley 25 carrying a pin 26, thus forming a crank which is rotated when the pin 27 is moved for abutment therewith, as will be readily understood.

20 The pulleys 25 and 28 are of the same diameter, and connected by a belt 28'. Each revolution of the pulleys rotates the main shaft 14 one revolution, and during one-half of each revolution the cam 29, fixed on the main shaft 14, forces the die 30 downward its full distance of travel and forms the flap, and immediately thereafter the operator removes his foot from the pedal 21, causing the disengagement of the elements 26 and 27, after which the stored energy in the pulley wheels, together with the reaction of the springs 29', which are compressed during the 25 downward movement of the die, acting on the cam, cause the shaft 14 to complete its revolution and remain at rest until the pedal is again depressed by the operator.

25 Mounted on the frame 10 is a base-plate 31, on which is fixed a pair of side frames, designated 32, 32, respectively, the upper ends of which are provided with bearings in which the main shaft 14 rests, and a numbering machine 33 is directly connected on an end of said shaft to register 30 each revolution thereof.

35 Fixed on the base plate 31 are two pillars 34, 34, respectively, which support the springs 29', 29', respectively, which in turn support a bridge 35, which is guided by the pillars and carries the die 30 on its under side and a thrust block 36 on its upper side for co-operation with the cam 29, which rests in contact therewith.

40 A housing formed with two side walls 37, 37, respectively, supports a platen 38 which is adapted to support the heel-flap of the shoe during the forming operation. This housing is slidably mounted upon the base-plate 31 (see Fig. 5), by means of guides 60 fixed to the base-plate, under the raised portions of which extend lateral flanges 61 at the lower edges of the walls 37.

Stops 62 at the rear of the guides 60, and fingers 63 on the side walls 37 which abut against adjustable screws mounted on the guides 60 as shown, limit the movement of the housing in each direction.

A guideway for the carriage 40 is formed at the lower sides of the walls 37 by the use of inwardly extending guide elements 39, 39, respectively, the carriage 40 resting directly on the top of the base-plate 31 and in sliding contact with the guide elements 39.

The carriage 40 is of greater length than the walls 37, and its front and rear ends are laterally extended to form shoulders, designated 65, 65, and 66, 66, respectively, thus providing for a predetermined sliding movement of the carriage relative to the housing as well as to the base-plate 31, and also for movement of the housing by the carriage, by abutment of either pair of shoulders 65 or 66, as the case may be.

The carriage is provided with a handle 41 at its outer end, and with slots 42 and 43. The slot 42 extends transversely, and a threaded rod 44 extends therethru and is held in rigid relation therewith by nuts 45 and 46, by means of which the rod may be raised and lowered in adjusting the height of a member 47, which member is also adjustable on said rod and is held in position by a set-screw 48.

The member 47 is provided with a ball-shaped upper end 49, which rests in a socket 50 formed in the lower end of threaded rod 51, a set-screw 52 holding these parts in relatively adjusted position.

The upper end of the rod 51 is formed to provide a pintle of usual construction, and a ring 53 adjustable on the thread thereof is used to form a base for the last 54 which rests thereon.

In the slot 43 is slidable a block 43', in which is non-rotatably fixed a rod 44', the lower portion of which is threaded to engage with lower and upper nuts 45 and 46 respectively. The nut 46 rides on the top surface of the carriage, and the nut 45 is adjusted to fit loosely against the under surface, to secure the lower end of the rod but at the same time permit the block to slide freely in the slot.

A spring 55 connects the block with the carriage, and serves to push the block and thereby the rod toward the outer or forward end of the carriage.

At the top of the rod 44' is a cross-rod 75, vertically and rotatably adjustable thereon and provided with a set-screw 76 (Fig. 6) by which it is held in adjusted position. A support for the toe of a shoe is carried on a sleeve 77, which is slideable and is also swingable on the cross rod, and adjustable in frictional but not rigid engagement in the desired position by a set-screw 78. The toe-support has a bell-shaped receptacle portion which is formed to provide yielding sections 51' which embrace the toe of the shoe 52 without marring it. The short sleeve 77 supporting this bell-shaped receptacle, may be placed upon either lateral arm of the cross-bar 75.

A resilient wire loop element 70 is pivotally mounted at a front portion of the platen, a finger 71 bearing against the front of the housing and normally causing the loop to lie flat upon the top of the platen 38. This loop is of a size and contour to lie within, and thus avoid, the line upon which the die 30 will cut. The heel-breast flap is slipped under the loop, and held in place thereby, as below mentioned.

The die 30 is shown provided with a resilient

pad of sponge rubber 30' filling the cavity thereof and extending to the cutting edges, which serves to flatten and smooth the flap prior to and during the forming operation, and to prevent rising of the flap on the upward return movement of the die. The die may be mounted on the bridge 35 in any desired manner. Due to the resiliency of the pad 30', the wire loop 70 does not interfere with its downward movement.

In placing the last, with the shoe thereon, in position for the forming operation, the carriage is first drawn forward to approximately its full extent. The rear shoulders 66 of the carriage engage the inner ends of the flanges 61 of the walls 37 and draw the housing forward into the position shown in Fig. 5. The housing is then forward of the die, and the shoe-supporting means on the carriage are in turn forward of the housing. The toe of the shoe is then placed in the bell-shaped receptacle 51' and pushed inwardly to compress the spring 55, and then in a swinging movement the last is placed on the pintle 51.

When placing the first of a series of shoes of one size and pattern, and either right or left, the pintle and its supporting parts are adjusted to correct position, laterally and angularly, and the screws and nuts tightened to retain such position; the bell-shaped receptacle is adjusted laterally, depending upon whether a right or a left shoe is to be operated upon, and also on its shape, and the height of the receptacle may be adjusted by vertical adjustment of the cross-rod 75 by its set-screw 76; the receptacle may then move swingingly on its support, and the block 43' moves longitudinally in the slot 43, against the tension of the spring 55, upon the insertion and removal of each individual shoe of the series.

Having placed the shoe on the carriage in position for correct presentation to the die, the carriage is first pushed rearwardly until the front shoulders 65 abut the flanges 61 on the lower edges of the walls 37 of the housing. The flap portion 53 of the sole is then folded over to lie upon the upper side of the platen in position for the die to act and form the flap to fit the breast of the heel of the shoe. The wire loop 70 holds the flap folded, the flap being either slid under, or, if more convenient, the loop being slightly lifted.

The carriage is then pushed in to its full extent, carrying the housing with it, and the shoe is in position for the flap-forming operation. The pedal is then depressed and the die lowered to cut the flap, and immediately thereafter the pedal is raised and the die is lifted to its normal position by action of the side springs 29' as before stated. The springs serve to prevent the die from being lowered until the pedal is again depressed, as will be readily understood.

Upon completion of the cutting operation, the carriage 40 is again drawn forward, its first movement being relative to the housing as well as to the base-plate 31. The formed flap is removed from under the loop 70, which is raised slightly if desired to prevent strain on the flap. As the forward motion of the carriage is continued, it again draws the housing forward into the position shown in Fig. 5. Upon removal of the shoe already operated upon, the parts are in adjusted position to receive another similar shoe, and the machine is operated as before. When a shoe of different size or shape is to be inserted, the new adjustments for the same are easily made.

The springs serve to prevent the die from again being lowered until the pedal is again depressed, as will be readily understood.

The means for adjusting the shoe flap in its proper position, for either a right or a left side shoe, and for holding the shoe in its adjusted position, are simple and effective, and the machine as a whole may be made at a lower cost than those heretofore made for a similar use, in so far as I am aware.

I do not limit myself to the particular details of construction and operation which have been shown and described, as it is obvious that the same refer to only one embodiment of my invention, and that the same may be modified, within the scope of the claims hereof, without departing from the spirit and scope of my invention.

Having thus described my invention, I claim as new:

1. A machine for forming heel flaps for shoes, comprising means for supporting a shoe provided with a heel in fixed position and a blank flap portion for covering the breast of said heel, means operative to cut a formed flap from said blank, means for positioning the shoe for the cutting operation with said heel out of the way of said cutting means, and means for operating said cutting means, comprising a rotatable cam disconnected from said cutting means, and operative during a part of a complete rotation to actuate said cutting means, means for moving said cutting means to inoperative position during another part of said rotation, and means for operating said cam.

2. A machine for forming heel flaps for shoes, comprising means for supporting a shoe provided with a heel in fixed position and a blank flap portion for covering the breast of said heel, a movable die operative to cut a formed flap from said blank, means for positioning the shoe with said heel out of the path of movement of said die and with said flap supported for the forming operation, and means for operating said die, comprising a rotatable cam disconnected from said die and operative during one part of a complete rotation to depress the same, means for operating said cam, and springs for raising said die.

3. The construction defined in claim 1, together with means for intermittently rotating said cam.

4. A machine for forming heel flaps for shoes, comprising a carriage mounted for reciprocative movement, means for supporting a shoe provided

with a blank flap portion for covering the breast of a heel, and means operative to provide a formed flap from said blank; said shoe-supporting means comprising a means adjustably mounted on said carriage for receiving the toe of a shoe carried on a last, and means for adjustably supporting the last.

5. A machine for forming heel flaps for shoes, comprising a carriage, means for supporting and guiding said carriage, means on said carriage for supporting a shoe provided with a blank flap portion for covering the breast of a heel, and means operative to provide a formed flap from said blank, said carriage being provided with a longitudinal slot and said shoe supporting means comprising means for receiving the toe of a shoe, said last mentioned means being movably mounted in said slot, and adjustable means for supporting a last carrying said shoe.

6. A machine for forming heel flaps for shoes, comprising a carriage mounted for reciprocative movement, means for supporting a shoe provided with a blank flap portion for covering the breast of a heel, and means operative to provide a formed flap from said blank: said shoe-supporting means comprising a means adjustably mounted with relation to said carriage for receiving the toe of a shoe carried on a last, and means angularly and vertically adjustable with relation to the carriage, for supporting said last, whereby movement of said carriage with said shoe in adjusted position thereon carries said shoe to a predetermined position relative to said forming means.

7. A machine for forming heel flaps for shoes, comprising a supporting frame, a housing supporting a platen and slidably mounted with relation to said frame, a carriage slidably mounted with relation to said frame and to said housing, means carried by said carriage for supporting a shoe provided with a blank flap portion for covering the breast of a heel, and means operative to cut a formed flap from said blank.

8. A machine for forming heel flaps for shoes, comprising a base-plate, a carriage slidably mounted thereon, means for guiding said carriage, means on said carriage for supporting a shoe provided with a heel attached thereto and a blank flap portion for covering the breast of a heel, a platen for supporting said blank flap portion, and a single cutting die operative to cut a formed flap from said blank.

LOUIS SABO.
